US00D778302S

(12) **United States Design Patent** (10) Patent No.: **US D778,302 S**
Leon et al. (45) Date of Patent: ** Feb. 7, 2017

(54) **DISPLAY SCREEN WITH GRAPHICAL USER INTERFACE**

(71) Applicant: **SOLAR TURBINES INCORPORATED**, San Diego, CA (US)

(72) Inventors: **Marco Ezra Leon**, San Diego, CA (US); **Garrett Linn Schiff**, San Diego, CA (US); **Neal Watkins**, Chula Vista, CA (US); **Thompson Hoang An Pham**, San Diego, CA (US); **Fabrice Mario Murgia**, San Diego, CA (US); **Vijaya Shankar Sadasivan**, San Diego, CA (US); **Pankaj Yogendra Tiwari**, San Diego, CA (US)

(73) Assignee: **Solar Turbines Incorporated**, San Diego, CA (US)

(**) Term: **15 Years**

(21) Appl. No.: **29/534,548**

(22) Filed: **Jul. 29, 2015**

(51) LOC (10) Cl. **14-04**

(52) U.S. Cl.

USPC **D14/486**

(58) **Field of Classification Search**

USPC **D14/485-495**

(57) **CLAIM**

The ornamental design for a display screen with graphical user interface, as shown and described.

DESCRIPTION

The sole FIGURE is a front view of a display screen with graphical user interface showing our new design.

The broken lines showing a phone bezel and a display screen form no part of the claimed design. Further, the broken lines shown within the display screen represent portions of the graphical user interface and form no part of the claimed design.

1 Claim, 1 Drawing Sheet
